Primary Examiner — Christy Nemeth*(74) Attorney, Agent, or Firm* — Tucker Ellis LLP(57) **CLAIM**

The ornamental design for a hook for surface and over-the-door mounting, as shown and described.

DESCRIPTION

FIG. 1 is a perspective view of a hook for surface and over-the-door mounting according to a first embodiment of our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a bottom view thereof;

FIG. 8 is a perspective view of the hook of FIG. 1 shown in an environment of use;

FIG. 9 is a perspective view of a hook for surface and over-the-door mounting according to a second embodiment;

FIG. 10 is a perspective view of a hook for surface and over-the-door mounting according to a third embodiment; and,

FIG. 11 is a perspective view of a hook for surface and over-the-door mounting according to a fourth embodiment. The broken lines in the drawings are for the purpose of illustrating environmental subject matter that forms no part of the claimed design.
